UNITED STATES PATENT OFFICE.

ELIZABETH ANN TRENNERY, OF MELBOURNE, VICTORIA, AUSTRALIA.

SAFETY HOOK AND EYE.

1,323,558.

Specification of Letters Patent.

Patented Dec. 2, 1919.

Application filed April 24, 1918. Serial No. 230,575.

To all whom it may concern:

Be it known that I, ELIZABETH ANN TRENNERY, a citizen of Australia, residing at Melbourne, in the county of Bourke, State 5 of Victoria, Australia, have invented certain new and useful Improvements in Safety Hooks and Eyes; and I do hereby declare the following to be a full, clear, and exact description of the invention, such as will enable others skilled in the art to which it 10 appertains to make and use the same.

This invention is an improvement in fasteners and has particular reference to a hook and eye.

15 An object of the invention is to provide an improved hook and eye which may be attached to the clothing without the necessity of sewing the same and without injury to the clothing.

20 Another object is to provide an improved means for retaining the hook in its attached position in the cloth so that accidental loss of the hook will be prevented.

A further object is to provide a fastener 25 of this character which is simple in construction, easy to manufacture and effective in carrying out the purpose for which it is designed.

The inventive idea involved is capable of 30 receiving a variety of mechanical expressions, some of which, for the purpose of illustrating the invention, are shown in the accompanying drawings wherein:

Figure 1 is a top plan view of the hook 35 and eye showing the same in locking position.

Fig. 2 is a perspective view of the hook.

Fig. 3 is a similar view of the eye.

Fig. 4 is a similar view of the locking or 40 retaining device for the hook.

Fig. 5 is a plan view of the hook showing another form of retaining device attached thereto.

Fig. 6 is a perspective view of the retaining or locking device shown in Fig. 5.

Referring to the accompanying drawings and more particularly to Figs. 1 to 4, it will be seen that the hook member is formed from a single length of wire bent upon itself intermediate its ends at 5 to form the tip of the bill 6 of the hook and also bent at 7 to provide the throat thereof. From the throat, the wire is carried back longitudinally beneath the bill to form the shank 8 of the

hook, and is then bent at 9 and carried outward and forward beyond the throat to form the longitudinally extending parallel pins 10. The free ends 11 of the pins 10 are curved slightly and sharpened so that the pins may be easily made to penetrate the 60 cloth in which the hook is secured, it being understood that, when the hook is secured in the cloth, the pins are made to penetrate the cloth from one side and then from the other.

65

The eye member which is associated with the hook is also formed from a single length of wire one end 12 of which is sharpened to provide a pin the inner end of which is bent to provide an eye or loop 13 adapted for engagement with the bill 6 and from said eye the material is extended, as indicated at 14 and then bent upon itself to provide the sharpened pin 15 which is disposed between the extended portion 14 and the pin or end 75 12 and which projects in the opposite direction from the latter. By the use of the pins 12 and 15, the eye may be embedded in the cloth with its loop or eye 13 disposed upon one side and the pins and extension 14 on 80 the other side thereof and in this manner it will be apparent that the loop 13 may be engaged by the bill 6 to connect the hook and eye together in operative relation.

In order to prevent accidental detachment 85 and consequent loss of the hook from the cloth, the same has associated therewith a locking or retaining device which is applied thereto when the hook is secured in position and this retaining or locking device, as 90 shown in Figs. 1 and 4, inclusive, is preferably formed from a single length of wire bent intermediate its ends to provide a loop 16 from which extend the parallel shanks 17 disposed in contacting relation. The outer 95 end of each shank is bent aside to provide the laterally extending pin receiving clip 18. In securing the hook in position, the loop 16 is first engaged with the bill 6 and the free ends of the pins 10 are then compressed or brought together so as to cause the same to pass between the spaced extremities of the clips 18, after which said free ends of the pins are released and owing to the resiliency of the wire the same will 100 return toward their normal positions into engagement with the bight portions of said clips whereby the hook member will be 105

locked in position and prevented from accidental detachment from the cloth.

The retaining or locking device shown in Figs. 5 and 6, is preferably stamped from a small piece of sheet metal to provide a body portion 19 one longitudinal edge of which is provided with a notch 20 shaped to form a loop which engages the bight portion 8 of the hook in a similar manner to the loop 16. The side edges of the body 19 are tapered and then bent upon themselves to provide the clips 21 which, similar to the clips 18, are adapted to receive the pins 10 of the hook member after the same has been 15 pressed and then engaged between said clips 21 and then released so as to contact said clips and be retained thereby.

What is claimed is:—

1. A fastener of the class described comprising a hook member formed from a single length of wire bent upon itself to provide a bill, a throat, a shank beneath the bill, and longitudinally extending pins projecting beyond the throat and adapted to penetrate 20 a piece of cloth, and an eye member formed from a single length of wire and bent upon itself to provide a loop engaging said bill and further bent at its extremities to provide longitudinally extending pins for penetrating the cloth.
2. A fastener of the class described comprising a hook member formed from a single length of wire bent upon itself to provide a bill, a shank and longitudinally extending pins projecting beyond the throat of said bill and adapted to penetrate a piece of cloth, an eye member formed from a single length of wire and bent upon itself to provide a loop engaging said bill and further bent at its extremities to provide longitudinally extending pins for penetrating the cloth, and a retaining device for one of said members including oppositely disposed clips for receiving the pins of the member

whereby to prevent detachment of the same 45 from the cloth.

3. A fastener of the class described comprising a hook member formed from a single length of wire bent upon itself to provide a bill and longitudinally extending pins projecting beyond the throat of said bill and adapted to penetrate a piece of cloth, an eye member formed from a single length of wire and bent upon itself to provide a loop 50 engaging said bill and further bent at its extremities to provide longitudinally extending pins for penetrating the cloth, and a retaining device formed from a single length of wire bent intermediate its ends to provide a loop for engaging the bill of said hook and also bent at its ends to provide oppositely disposed clips for receiving the pins of the hook whereby the latter will be retained in its position in the cloth.

4. A fastener of the class described comprising a hook member including pins adapted to penetrate a piece of cloth, an eye member associated with said hook, and a retaining device for the hook having a portion thereof adapted for engagement with 70 the bill of the hook and also having clips for receiving the pins of the hook.

5. In a fastener of the class described, a hook member including pins adapted to penetrate a piece of cloth, and a retaining device formed from a single piece of material having a loop for engaging in the throat 75 of the hook and also having its lateral ends bent upon themselves to form clips for receiving the pins of the hook whereby to retain the latter in position in the cloth.

In testimony whereof, I affix my signature, in the presence of witnesses.

ELIZABETH ANN TRENNERRY.
